UNITED STATES PATENT OFFICE.

ANDREW JACKSON WRIGHT, OF WRIGHTSVILLE, ILLINOIS.

HAY-RACK.

SPECIFICATION forming part of Letters Patent No. 355,241, dated December 28, 1886.

Application filed October 15, 1886. Serial No. 216,356. (No model.)

To all whom it may concern:

Be it known that I, ANDREW JACKSON WRIGHT, a citizen of the United States, residing at Wrightsville, in the county of Greene 5 and State of Illinois, have invented a new and useful Improvement in Hay-Racks, of which the following is a specification.

My invention relates to an improvement in hay-racks for wagons; and it consists in the peculiar construction and combination of devices 10 that will be more fully set forth hereinafter, and particularly pointed out in the claims.

In the drawings, Figure 1 is a perspective view of a hay-rack embodying my improvements. Fig. 2 is a vertical transverse sectional view of the same. Fig. 3 is a vertical longitudinal sectional view. Fig. 4 is a bottom plan view. Fig. 5 is a perspective view showing the wings removed and the hinged 20 end frames in the vertical position to adapt the rack for hauling cord-wood, baled hay, &c.

A represents the bed of the rack, composing the longitudinal beams B, the transverse connecting-bars C on the under sides of the beams, 25 and the transverse end bars, D, on the upper sides of the beams. The said end bars have their outer ends projecting beyond the outer sides of the beams B, thereby forming stops D', for the purpose to be hereinafter described.

E represents end frames, which comprise the side arms, F, and the transverse slats G, which connect the outer ends of the said arms. The lower ends of the arms F are pivoted to the outer sides of the beams D, near the ends thereof, as at H. It will be seen that the end frames are thus pivoted to the ends of the bed, and are adapted to be folded down upon the same, as shown in dotted lines in Fig. 5, or to be raised to a vertical position, as shown in solid lines 40 in the remaining figures of the drawings. When the end frames are elevated to a vertical position, they bear against the stops D', and are thus prevented from swinging outwardly from the ends of the bed.

I represents side beams, which comprise the longitudinal slats K and the supporting-bars L, which are arranged at right angles to the slats, and to the outer ends of which the said slats are attached. These supporting-bars are 50 each provided on their inner ends with notches M, thereby forming feet which are adapted to

engage the under side of one of the beams B. On the under side of each supporting-bar L, at a suitable distance from the outer end thereof, is made a notch, N. The wings are 55 secured to opposite sides of the bed by having their supporting-bars L resting on the upper edge of one of the beams B, and with their feet bearing under the lower side of the opposite beam B, the supporting-bars of the two 60 wings being crossed, as shown in Fig. 2.

It will be noted that the notches N are on a higher plane than the upper side of the cross-bars C, and thereby openings are formed to admit the insertion of a longitudinal key-board, 65 O, between the said notches and the upper side of the cross bars. This key-board extends the whole length of the bed, and locks the cross-bars of the wings firmly together and to the side beams of the bed, so that it is impossible 70 for the wings to become accidentally detached from the bed. The key-board also forms the bottom board for the rack.

The wings are light, and may be readily attached to the bed or detached therefrom by one 75 man, thus saving the heavy lifting which is necessary to place the ordinary hay-racks on the running-gear of a wagon.

When the wings are removed from the bed and the end frames turned upwardly, as 80 shown in Fig. 5, the rack is adapted for hauling cord-wood, corn-fodder, baled hay, and similar articles.

Having thus described my invention, I 85 claim—

1. The combination of the wagon-bed having the side beams, B, the detachable side wings having the supporting-bars L, the lower ends of which engage the under sides of the beams B, and the removable key-board O, to bear 90 against the bars L and hold them in engagement with the beams B, and thereby lock the side wings to the bed, substantially as described.

2. In a hay-rack for wagons, the combination of the bed having the cross-bars D, the ends of which are extended to form the stops D' at the ends thereof, the removable side wings for the bed, and the end frames, E, pivoted or hinged to the ends of the bed, and adapted to engage the stops D' when raised to a vertical position, substantially as described. 95 100

3. The hay-rack for wagons, comprising the bed having the longitudinal beams B and the cross-bars C on the under sides thereof, in combination with the side wings having the supporting bars L, the lower ends of which engage the under sides of the beams B, and the key-board O, inserted between the bars L and bearing upon the upper side of the bar C, whereby the side wings are secured firmly to the bed, substantially as described.

4. In a hay-rack for wagon-beds, the com-

bination, with the beams B, of the side wings having the bars L, engaging the beams, and the key-board O, for locking the bars L against the beams, as set forth.

15

In testimony that I claim the foregoing as my own I have hereto affixed my signature in presence of two witnesses.

ANDREW JACKSON WRIGHT.
